FISHING REEL

Victor Yeada, Denver, Colo., assignor to Wright &
McGill Co., Aurora, Colo., a corporation of Colorado

Filed Feb. 13, 1961, Ser. No. 63,927

Term of patent 14 years

(Cl. D31—4)

Fig. 1

Fig. 2

Fig. 3

Fig. 4

Fig. 7

Fig. 6

Fig. 5

FIG. 1 is a right side elevational view of a fishing reel showing my new design;

FIG. 2 is a rear elevational view thereof;

FIG. 3 is a front elevational view thereof;

FIG. 4 is a left side elevational view;

FIG. 5 is a top plan view thereof;

FIG. 6 is a cross-sectional view of the housing portion of the reel taken along line 6-6 of FIG. 3; and

FIG. 7 is an enlarged fragmentary cross-sectional view along line 7-7 of FIG. 1 showing the pattern of ornamentation appearing on the perimeter of the housing portion.

I claim:

The ornamental design for a fishing reel, as shown.
